J. T. Bryant
ATTORNEY.

UNITED STATES PATENT OFFICE.

BEN WILLIAMSON, OF ASHLAND, KENTUCKY.

ACETYLENE LAMP.

Application filed April 13, 1928. Serial No. 269,758.

The present invention relates to improvements in acetylene lamps, and more particularly to the dropper or valve controlled communication between the water and carbide containers.

The principal object of the present invention is to provide certain improvements in the construction described and claimed in the U. S. Patent M. Stein, No. 1,376,654, dated 10 May 3d, 1921.

Briefly stated, the present invention aims to provide means for slidably keying the valve stem to the screw threaded adjusting sleeve, in combination with means for longitudinally adjusting the valve stem relative to the dropper tube and the adjusting sleeve, whereby to obtain an adjustment of the dropper valve relative to its seat or the lower end of the dropper tube, independent of the opening 20 and closing movement of the valve by turning of the adjusting sleeve, for setting the valve so as to properly function even though the same is worn by reason of continued use.

A further object is to provide for attachment of the operating handle for the adjusting sleeve to the latter in such manner that said handle will not break loose from the sleeve and cease to function.

Still another object is to provide a swivel 30 connection between the operating handle of the adjusting sleeve and the adjusting nut for the valve stem, whereby positive downward adjustment of the valve stem is insured upon mere rotation of the adjusting nut, and whereby detachment and loss of the adjusting nut is prevented.

Other objects will appear as the nature of the invention is better understood, and the same consists in the novel form, combination 40 and arrangement of parts hereinafter more fully described, shown in the accompanying drawing and claimed.

In the drawing:—

Figure 1 is a view, partly in elevation and 45 partly in vertical section, of an acetylene lamp constructed in accordance with the present invention;

Figure 2 is an enlarged fragmentary vertical section showing details of the dropper device;

Figure 3 is a horizontal section on line 3—3 of Figure 2;

Figure 4 is a horizontal section on line 4—4 of Figure 2; and

Figure 5 is an enlarged perspective view of

the operating handle for the adjusting sleeve and the attached nut for adjusting the valve stem.

Referring more in detail to the drawing, 4 indicates the water container and 5 the carbide container, located beneath the water container 4 and detachably secured thereto in the usual well known manner.

The containers 4 and 5 are divided by the usual septum, not shown, and a suitable filling 65 opening 11 is provided in the top of the water container and furnished with a cover 12.

Extending through the top and bottom of the water container is a dropper which comprises an open ended tube 13 having a hole 70 communicating with the water chamber 4 in the usual way. The tube 13 is internally threaded as at 15 at its upper end, said tube being secured in place permanently by soldering or the like at the top and bottom of the 75 container.

Extended through the tube 13 and projecting at both ends therefrom is a stem 16 which is threaded at its upper end and provided adjacent its upper end with a pair of swaged 80 wings 17 which are elongated longitudinally of the stem 16 and serve as keys to prevent relative rotation between the stem 16 and the externally threaded sleeve 18, while permitting longitudinal adjustment of the stem 85 16 relative to the latter. The externally threaded sleeve 18 has slots 19 for fitting over the wings 17 of the stem 16. The sleeve 18 is threaded to the threads 15 of the tube 13, and the stem 16 has its body flattened to form the 90 wings 17 as clearly shown.

For adjusting the stem 16 longitudinally or vertically relative to the tube 13 and sleeve 18, a nut 20 is provided which is threaded upon the stem 16 and disposed upon the sleeve 95 18 to hold the keying devices or wings 17 and slot 19 locked in adjusted relationship.

For convenience in rotating the sleeve 18 to raise and lower the stem 16, a handle 21 is provided which is permanently secured to the 100 sleeve and which is constructed of resilient metal so as to operate as a tension device to hold the sleeve against ready rotation, as required to maintain and establish water flow. As shown, the nut 20 is provided with a 105 reduced lower end portion which is attached and swiveled in an opening in the inner end of the handle 21 as generally indicated at 25, and a depending sleeve 26 is provided on the inner end of the handle 21 which is snugly fitted 110

over the head or upper end of the sleeve 18 and firmly pressed thereon against accidental upward removal. As the nut 20 is thus held against upward movement when rotated to 5 adjust the stem 16 downwardly, downward adjustment of the stem 16 is positively insured. The head or upper end of the sleeve 18 is provided with a lateral projection 27, and formed in the inner side of the sleeve 26 10 is a slot 28 through which the projection 27 extends. The projection 27 is of a width substantially corresponding to the width of the slot 28, and in this way, the handle 21 is keyed to the sleeve 18 so that the latter is positively turned upon operation of the handle 21, as will be obvious. By reason of this construction, it is insured that the handle will remain operative for its intended purpose, thereby overcoming the objectionable 15 tearing loose of the handle from the stem as has heretofore been experienced when the handle is simply soldered upon the upper end of the sleeve as in the patent above mentioned.

20 To the lower end of the stem 16 there is secured a valve 22 provided with a bottom flange 23 and with a cone 24 which cooperates with the lower end of the dropper tube 13 to control the flow or dropping of water from 25 the water container 4 to the carbide container 5.

It will be obvious that upon rotation of the nuts 20 in one direction, the stem 16 will be positively adjusted downwardly in case its 30 removal from the tube 13 is desired. Upon removal of the stem 16 the sleeve 18 may be readily threaded out of the tube 13 if necessary for purposes of cleaning and repair. On the other hand, when the nut 20 is rotated in 35 the opposite direction, the stem 16 may be adjusted upwardly so as to set the cone 24 closer to the lower end of the tube 13 for a given adjustment of the sleeve 18, thereby adjusting or compensating for wear of the valve 22 after 40 continued use.

From the above description it will be seen that the stem is slidably keyed to the sleeve 18 instead of being simply held engaged therewith, the nut 20 being used for material 45 and intentional adjustment of the stem 16 to adjust the valve 22 for compensating for wear. As the handle 21 is fixed to the sleeve 18 and the nut 20 is attached to the handle 21, the downward adjustment of stem 16 is positively 50 effected merely upon turning the nut 20, no downward force being necessary upon the rod 16 after turning the nut 20 as is required when the nut merely engages the upper face

of the handle as shown in the patents mentioned above.

60 Minor changes may be made without departing from the spirit and scope of the invention as claimed.

What I claim as new is:—

1. A dropper for acetylene lamps comprising a tube open at both ends, a sleeve having a threaded connection with the tube, a stem slidably extended through the tube and sleeve, a valve carried by the stem, means for slidably keying the stem to the sleeve, a handle for 65 rotating the sleeve, a nut for adjusting the stem longitudinally relative to the sleeve with their keying means relatively engaged, said sleeve having a head at its upper end, and a second sleeve on the inner end of the handle 70 snugly fitted and pressed over the head of said threaded sleeve.

2. A dropper for acetylene lamps comprising a tube open at both ends, a sleeve having a threaded connection with the tube, a stem slidably extended through the tube and sleeve, a valve carried by the stem, means for 75 slidably keying the stem to the sleeve, a handle for rotating the sleeve, a nut for adjusting the stem longitudinally relative to the sleeve with their keying means relatively engaged, said sleeve having a head at its upper end, and a second sleeve on the inner end of the handle 80 snugly fitted and pressed over the head of said threaded sleeve, said head of the threaded sleeve having a lateral projection, said sleeve of the handle having a slot at its inner side snugly receiving said projection to key the handle to the threaded sleeve.

3. A dropper for acetylene lamps comprising a tube open at both ends, a sleeve having a threaded connection with the tube, a stem slidably extended through the tube and sleeve, a valve carried by the stem, means for slidably keying the stem to the sleeve, a handle for 90 rotating the sleeve, a nut for adjusting the stem longitudinally relative to the sleeve with their keying means relatively engaged, said sleeve having a head at its upper end, and a second sleeve on the inner end of the handle 95 snugly fitted and pressed over the head of said threaded sleeve, said head of the threaded sleeve having a lateral projection, said sleeve of the handle having a slot at its inner side snugly receiving said projection to key the handle to the threaded sleeve, said nut being swiveled to the inner end of the handle.

In testimony whereof I affix my signature.
BEN WILLIAMSON.
